CLAIM

The ornamental design for a transcatheter device for treating tricuspid valve regurgitation, as shown and described.

DESCRIPTION

FIG. 1 is a front view of a transcatheter device for treating tricuspid valve regurgitation;

FIG. 2 is a rear view thereof;

FIG. 3 is a left-side enlarged view of the 3-3 portion of FIG. 1

FIG. 4 is a right-side enlarged view of the 4-4 portion of FIG. 1

FIG. 5 is a top view of the transcatheter device for treating tricuspid valve regurgitation;

FIG. 6 is a bottom view of the transcatheter device for treating tricuspid valve regurgitation;

FIG. 7 is an enlarged view of the 7-7 portion of FIG. 1; and,

FIG. 8 is an enlarged view of the 8-8 portion of FIG. 2. The break lines in the figures indicate that the appearance of any portion of the transcatheter device for treating tricuspid valve regurgitation between the break lines forms no part of the claimed design.
